UNITED STATES PATENT OFFICE.

WILLIAM TWEEDDALE, OF BROOKLYN, ASSIGNOR TO THE NORTH AMERICAN IRON WORKS, OF NEW YORK, N. Y.

DESIGN FOR A SETTEE.

SPECIFICATION forming part of Design No. 20,729, dated May 19, 1891.

Application filed March 13, 1891. Serial No. 384,955. Term of patent 14 years.

To all whom it may concern:

Be it known that I, WILLIAM TWEEDDALE, a citizen of the United States, residing at Brooklyn, in the county of Kings and State of New York, have invented and produced a new and original Design for a Settee, of which the following is a specification, reference being had to the accompanying drawings, forming part thereof.

10 Figure 1 is a front elevation of a settee, showing my design. Fig. 2 is an end elevation of the same; and Fig. 3 is a partial plan view showing the design of the seat, these three views being deemed necessary to fully illustrate my design.

15 The leading feature of my design is the open-work arabesque scroll and leaf scroll ornaments and the surrounding bars forming the panel designs and the open-work seat and arabesque seat ornaments.

20 In the design for the settee-back, *a*, *b*, *b'*, *c*, and *c'* represent the panels. The design of the panel *a* comprises the border *d*, which is square in general contour, the arabesque scroll and leaf ornaments *d'*, the central ornament *e*, and oval ring ornament *e'*. Above these are the diverging scroll ornaments *e*², with the upper scroll and multi-foil ornaments at *f*. The design of each of the panels *b* *b'* is alike, and comprises the border *g*, which is square in general contour and has circular raised knob ornaments, the arabesque scroll and leaf scroll ornaments *h*, with the upper shield-pattern and scroll ornaments *h'*. The design of each of the panels *c* *c'* is alike, and comprises the border *i*, which is oblong or rectangular in shape or general contour and has circular raised knob ornaments and the arabesque scroll and leaf ornaments *i'*, with the upper scroll ornaments *i*².

25 The design of the seat of the settee comprises the border *k*, the ring ornaments *l*, the diagonal X-bars *l'*, and intersecting ornaments *m* and the quarterfoil ornaments *m'*.

30 The design of the edge of the settee comprises the raised ribs and circular raised

knob ornaments *n* and the edge scroll and knob ornaments *n'*.

The design of the end of the settee (illustrated in Fig. 2) comprises the curved back 50 leg *o*, the curved front leg *o'*, the curved seat-piece *o''*, the curved arm-piece *r*, the arm-piece and front leg having leaf and other ornaments, as shown, the curved base-bar *r'*, and the arabesque scroll and leaf scroll ornaments 55 *s* converging thereto, and the scroll and leaf ornaments *s'* and medallion ornaments *t*.

At the top of the back is a leaf and knob ornament *t*, and at the lower ends of the back and front legs, respectively, are ornaments *u* *u'*.

What I claim is--

1. The design of the ornamental shape and configuration of the settee, substantially as shown and set forth. 65

2. In the design for a settee herein shown and described, the design of the back-panel *a*, the same comprising the arabesque scroll and leaf ornaments *d'*, the central ornament *e*, the oval ring ornament *e'*, the diverging 70 scroll-line ornaments *e*², and scroll and multi-foil ornaments at *f*, as set forth.

3. In a design for a settee herein shown and described, the design of the back-panel *b*, the same comprising a border with raised 75 knob ornaments and the arabesque scroll and leaf scroll ornaments, as set forth.

4. In a design for a settee herein shown and described, the design of the back-panel *c*, the same comprising a border of raised 80 knob ornaments and the arabesque scroll and leaf ornaments, as set forth.

5. In a design for a settee herein shown and described, the design of the ornamental shape and configuration of the ends, substantially as shown and set forth. 85

Signed by me this 9th day of March, A. D. 1891.

WILLIAM TWEEDDALE.
